UNITED STATES PATENT OFFICE

HARRY B. HULL, OF DAYTON, OHIO, ASSIGNOR TO FRIGIDAIRE CORPORATION, OF DAYTON, OHIO, A CORPORATION OF DELAWARE

REFRIGERATING APPARATUS

Application filed November 27, 1929. Serial No. 410,151.

This invention relates to refrigerating apparatus and more particularly to a refrigerating apparatus or system having a plurality of refrigerating surfaces which may be maintained at different temperatures.

An object of this invention is to provide a refrigerating system wherein different temperatures may be maintained in different evaporating sections without the use of an automatic valve in the suction side of the system.

Another object of this invention is to provide a novel method of maintaining different pressures in different evaporators connected to the same compressor.

Further objects and advantages of the present invention will be apparent from the following description, reference being had to the accompanying drawings, wherein a preferred form of the present invention is clearly shown.

In the drawings:

Fig. 1 is a view, somewhat diagrammatic, of a refrigerating system embodying features of this invention;

Fig. 2 is a view, also somewhat diagrammatic, of another system;

Fig. 3 is a view, somewhat diagrammatic, of another system;

Fig. 4 is a view, partly in section, of a portion of the apparatus shown in Figs. 1 to 3 inclusive, and

Fig. 5 is an enlarged cross sectional view of a portion of the apparatus shown in Figs. 2 and 3.

Fig. 6 is a sectional view of either of the float chambers of the evaporators shown in Fig. 1.

A refrigerating system embodying features of this invention may include a refrigerant low pressure side and a refrigerant high pressure side. A refrigerant liquefying unit 20 may transfer evaporated refrigerant from the low pressure side as liquid refrigerant to the high pressure side. A plurality of evaporating sections or evaporators 21, 22 may transfer liquid refrigerant from the high pressure side as evaporated refrigerant to the low pressure side. Thus a liquid refrigerant line 23 may connect said refrigerant liquefying

unit 20 and said evaporators to form the refrigerant high pressure side. The low pressure side may include an evaporated refrigerant line 24 connecting said refrigerant liquefying unit 20 and at least one of said evaporators, such as evaporator 22, an evaporated refrigerant branch 25 connecting said evaporated refrigerant line and at least another of said evaporators, for instance evaporator 21 to form the refrigerant low pressure side. The evaporated refrigerant line 24 may be provided with means for creating in said line a zone of lower pressure of the refrigerant than in the main portion of said line. Such means is generally indicated at 26, and the branch 25 may connect the evaporator 21 with the zone heretofore described in means 26. The refrigerant liquefying unit 20 may be controlled in accordance with conditions in the refrigerating system, and preferably the unit may be controlled in accordance with pressures of the expanded refrigerant. This may be accomplished by a pipe or connection 27 leading from the line 24 to a control device 28 for controlling the operation of the unit 20.

The refrigerant liquefying unit 20 may be of any suitable construction. Thus it may include a compressor 30 driven by an electric motor 31. The compressed refrigerant from the compressor 30 may be condensed in a condenser 32, the lower portion of which may be provided with a liquid refrigerant receiver, which may be of enlarged cross section, but is shown here merely as the lower section 33 of the condenser 32. From the condenser 32 or receiver 33 the liquid refrigerant may be conveyed by the liquid refrigerant line 23 to the evaporators 21, 22. This may be accomplished by providing branches 34 and 35 leading to the evaporating sections or evaporators 21, 22 which evaporators may be of the flooded type and preferably of the float controlled valve type shown in the patent to R. G. Osborn 1,556,708, patented October 13, 1925. A cross section of the float chambers of the evaporators 21 and 22 is shown in Fig. 6. This figure shows a needle valve 91 operated by the float ball 92 to admit sufficient liquid refrigerant from the conduit 100

23 to maintain liquid refrigerant within the float chamber to the proper level as shown at 93. The vaporized refrigerant within the float chamber is withdrawn through the outlet duct 94. Thus there is provided means 5 for independently controlling the flow of refrigerant into said evaporating sections. The evaporated refrigerant may return to the liquefying unit 20 through the branch or branches 25 and evaporated refrigerant line 10 24 to the compressor and preferably to the crank case as shown.

If the refrigerant liquefying unit is intermittent in operation, and electrically driven, the motor 31 may be started and stopped by the control device 28 which may include the snap switch 36 connected to an expansible chamber 37, which in turn may be connected by the connection or pipe 27 with the expanded refrigerant, and preferably at the expanded refrigerant line 24.

The construction is such that a different pressure may be maintained, through at least a part of the operating time, in the evaporators 21 and 22. Means 26 creates a zone of lower pressure of the refrigerant in the line 24. This may be accomplished by any suitable means such as any constriction, jet or venturi construction. Thus the constriction 30 may include a jet 40 which may be part of the venturi 41. This construction creates a zone at 42 wherein the pressure of the expanded refrigerant is substantially less than in the main portion of the refrigerant line 24. The branch 25 may be connected to the zone 42, for instance, by means of the passage 43 in the Venturi fitting leading from the zone 42. Thus it is to be seen that the lower pressure of the zone 42 is submitted to the evaporator 21 and thus maintains that evaporator at a lower pressure than the evaporator 22, at least during the period of operation of the compressor.

The evaporators may be placed in any suitable containers. Thus as shown in Fig. 1 the evaporator 21 may be placed in an ice cream cabinet 50, which, if desired, may be a part of an ice cream soda fountain, and may contain suitable sleeves 51 for receiving the usual food or ice cream containers. These sleeves 50 may be immersed in brine 52 placed in the brine tank 53 in a manner well known. Evaporator 22 may be placed in a liquid cooling compartment of the fountain. Thus it 55 may be placed in the tank 54 without the addition of any freezing compositions. One or more coils 55 may be immersed in the water for cooling the liquids such as drinking water, carbonated water, etc. generally used in soda fountains.

In the modification shown in Fig. 2, the evaporating sections may be applied to what is ordinarily considered a single cooling unit. Thus the refrigerant liquefying unit 20a may 60 deliver liquefied refrigerant to the cooling

unit 60. The cooling unit 60 may include two or more surfaces or sections adapted to be maintained at different temperatures. Thus an air cooling surface 61 may be provided and a freezing surface or section 62 70 may also be provided. The air cooling surface or section 61 preferably may be a spiral wound around, but spaced from the cooling surface or section 62. The surface 62 may also be a spiral wound around and contacting with the surface 63 which may be an ice tray sleeve. The cooling unit 60 may be placed in insulated food compartment substantially in the manner shown in the Australian patent to Delco-Light Company, No. 10,380/27. The difference in temperature in the surface or sections 61 and 62 may be obtained by the use of means 26a, similar to means 26 heretofore described. A single expansion valve 64, or independent valves for each of the surfaces or sections 61 and 62 80 may be provided. If a single expansion valve 64 is provided, part of the refrigerant will follow pipe or section 61, and part will follow pipe or section 62. Since the means 26a produces a lower pressure in the pipe or section 62, the temperature in this pipe is lower than the temperature in pipe 61.

In order to insure a lower pressure in the pipe 62 a suitable construction 62' may be placed in the T fitting 64' and leading to the pipe 62 which provides sufficient resistance or expansion to permit a lower pressure in pipe 62. The fitting 64' may be sufficiently close to the valve 64 to be a part 90 of the expansion means for the coil 62, thus providing means for independently controlling the flow of refrigerant into said pipe sections. In this modification the refrigerant liquefying unit 20a may be controlled by a thermostatically operated control device 28a, which may include snap switch 36a controlling the operation of the motor 31a. The expansible chamber 37a operating switch 36a 100 may be connected by a pipe 27a to a thermostatic bulb 65, which is responsive to conditions in the refrigerating system, and preferably to temperature conditions in the sleeve 63.

In the modification shown in Fig. 3 the 115 refrigerant liquefying unit 20b may discharge liquid refrigerant into the expansion valve 64b from whence the expanded refrigerant branches at the fitting 64' into pipe or evaporating sections 61b and 62b. The construction 62' may lead to the pipe 62b. The pipe or evaporating section 61b 120 may be used to cool food storage cabinet by means of the coil 70, while the pipe or evaporating section 62b may be used to cool an ice cream cabinet in any suitable manner. Thus it may be branched into coils 71, 72 and 73 surrounding the sleeves 74, which are provided for the reception of ice cream cans or the like. The ice cream cabinet may, if de- 130

sired, be provided with a tank 75 and may be filled with brine, or, if desired, the space may be filled with insulating material so that the refrigerant of each sleeve is independent of the remainder of the sleeves. The branches 71, 72 and 73 may be joined into the branch 25b which leads to the device 26b similar to device 26 and from thence the refrigerant returns through the expanded refrigerant line 24b. The motor 31b may be controlled by a thermostatic device 28b including a snap switch 36b operated by an expansible bellows 37b which may be connected through the pipe 27b with a thermostatic bulb 65b conveniently placed in the brine tank 75.

Unless otherwise described, or as well understood from the inherent difference, the parts shown in the different modifications operate substantially in the same manner.

While the form of embodiment of the invention as herein disclosed constitutes a preferred form, it is to be understood that other forms might be adopted, all coming within the scope of the claims which follow.

What is claimed is as follows:

1. A refrigerating system comprising a refrigerant liquefying unit, a plurality of evaporating sections, a liquid refrigerant line connecting said unit and said sections, an evaporated refrigerant line connecting said unit and one of said sections, means in said evaporated refrigerant line creating in said line a zone of lower pressure of the refrigerant than in the main portion of said line, and an evaporated refrigerant branch connecting said zone and another of said sections.

2. A refrigerating system comprising a refrigerant liquefying unit, a plurality of evaporating sections, a liquid refrigerant line connecting said unit and said sections, an evaporated refrigerant line connecting said unit and one of said sections, means in said evaporated refrigerant line creating in said line a zone of lower pressure of the refrigerant than in the main portion of said line, and an evaporated refrigerant branch connecting said zone and another of said sections and means responsive to evaporated refrigerant pressure for controlling the operation of said unit.

3. A refrigerating system comprising a refrigerant liquefying unit, a plurality of evaporating sections, a liquid refrigerant line connecting said unit and said sections, an evaporated refrigerant line connecting said unit and one of said evaporators, jet means in said evaporated refrigerant line creating in said line a zone of lower pressure of the refrigerant than in the main portion of said line, and an evaporated refrigerant branch connecting said zone and another of said sections.

4. A refrigerating system comprising a refrigerant liquefying unit, a plurality of

evaporating sections, a liquid refrigerant line connecting said unit and said evaporating sections, an evaporated refrigerant line connecting said unit and one of said evaporating sections, a venturi in said evaporated refrigerant line creating in said line a zone of lower pressure of the refrigerant than in the main portion of said line, and an evaporated refrigerant branch connecting said zone and another of said evaporating sections.

5. A refrigerating system comprising a refrigerant liquefying unit, a plurality of evaporating sections, a liquid refrigerant line connecting said unit and said evaporating sections, means independently controlling the flow of refrigerant into said evaporating sections, an evaporated refrigerant line connecting said unit and one of said evaporating sections, means in said evaporated refrigerant line creating in said line a zone of lower pressure of the refrigerant than in the main portion of said line, and an evaporated refrigerant branch connecting said zone and another of said evaporating sections.

6. A refrigerating system comprising a refrigerant liquefying unit, a plurality of evaporating sections, a liquid refrigerant line connecting said unit and said evaporating sections, means in said evaporating sections for independently maintaining a quantity of liquid refrigerant in said evaporating sections, an evaporated refrigerant line connecting said unit and one of said evaporating sections, means in said evaporated refrigerant line creating in said line a zone of lower pressure of the refrigerant than in the main portion of said line, and an evaporated refrigerant branch connecting said zone and another of said evaporating sections.

7. A refrigerating system comprising a refrigerant liquefying unit, a plurality of evaporating sections, a liquid refrigerant line connecting said unit and said evaporating sections, float controlled valves in said evaporating sections for independently maintaining a quantity of liquid refrigerant in said evaporating sections, an evaporated refrigerant line connecting said unit and one of said evaporating sections, means in said evaporated refrigerant line creating in said line a zone of lower pressure of the refrigerant than in the main portion of said line, and an evaporated refrigerant branch connecting said zone and another of said evaporating sections.

8. A refrigerating system wherein refrigerant flows comprising a refrigerant low pressure side, and a refrigerant high pressure side, a refrigerant liquefying unit for transferring evaporated refrigerant in the low pressure side as liquid refrigerant to the high pressure side, a plurality of evaporating sections for transferring liquid refrigerant from the high pressure side as evaporated refrigerant in the low pressure side, means uti-

lizing the flow of refrigerant for creating different pressures in at least two of said evaporating sections.

9. A refrigerating system wherein refrigerant flows comprising a refrigerant low pressure side, and a refrigerant high pressure side, a refrigerant liquefying unit for transferring evaporated refrigerant in the low pressure side as liquid refrigerant to the high pressure side, a plurality of evaporating sections for transferring liquid refrigerant from the high pressure side as evaporated refrigerant in the low pressure side, means utilizing the flow of refrigerant in the low pressure side for creating different pressures in at least two of said evaporating sections.

10. A refrigerating system comprising a refrigerant liquefying unit, a plurality of evaporating sections, a liquid refrigerant line connecting said unit and said evaporating sections, an expansion valve for controlling the supply of liquid refrigerant to said sections, an evaporated refrigerant line connecting said unit and one of said evaporating sections, means in said evaporated refrigerant line creating in said line a zone of lower pressure of the refrigerant than in the main portion of said line, and an evaporated refrigerant branch connecting said zone and another of said evaporated sections.

11. A refrigerating system comprising a refrigerant liquefying unit, an inner evaporating section for creating a freezing zone, an outer evaporating section for cooling air, a liquid refrigerant line connecting said unit and said evaporating sections, means for controlling the supply of liquid refrigerant to said evaporating sections, an evaporated refrigerant line connecting said unit and the outer of said evaporating sections, means in said evaporated refrigerant line creating in said line a zone of lower pressure of the refrigerant than in the main portion of said line, and an evaporated refrigerant branch connecting said zone and the inner of said evaporating sections.

In testimony whereof I hereto affix my signature.

HARRY B. HULL.
